(57) **CLAIM**

The ornamental design for a power distribution device, as shown and described.

DESCRIPTION

FIG. 1 is a perspective view of a power distribution device showing my new design;

FIG. 2 is an alternate perspective view of the power distribution device of FIG. 1;

FIG. 3 is an alternate perspective view of the power distribution device of FIG. 1;

FIG. 4 is a front view of the power distribution device of FIG. 1;

FIG. 5 is a right side view of the power distribution device of FIG. 1;

FIG. 6 is a left side view of the power distribution device of FIG. 1;

FIG. 7 is top view of the power distribution device of FIG. 1;

FIG. 8 is a perspective view of an alternate embodiment of a power distribution device showing my new design;

FIG. 9 is an alternate perspective view of the power distribution device of FIG. 8;

FIG. 10 is an alternate perspective view of the power distribution device of FIG. 8;

FIG. 11 is a front view of the power distribution device of FIG. 8;

FIG. 12 is a right side view of the power distribution device of FIG. 8;

FIG. 13 is a left side view of the power distribution device of FIG. 8;

FIG. 14 is a top view of the power distribution device of FIG. 8; and,

FIG. 15 is a rear view of the power distribution device of FIGS. 1–7 and a rear view of the power distribution device of FIGS. 8–14.

The bottom view of the power distribution device of FIGS. 1–7 and 8–14 is not shown and does not form part of the claimed design. In the drawings, a cord and plug prongs of the power distribution device are shown in dashed lines and do not form part of the claimed design.
